UNITED STATES PATENT OFFICE.

JAMES REAGAN AND WILLIAM REAGAN, OF PHILADELPHIA, PENNSYLVANIA; SAID WILLIAM REAGAN ASSIGNOR TO SAID JAMES REAGAN.

MECHANICAL STOKER.

No. 925,723.

Specification of Letters Patent. Patented June 22, 1908.

Application filed May 5, 1908. Serial No. 430,980.

To all whom it may concern:

Be it known that we, JAMES REAGAN and WILLIAM REAGAN, citizens of the United States, residing in the city and county of 5 Philadelphia, State of Pennsylvania, have invented a new and useful Mechanical Stoker, of which the following is a specification.

Our invention consists of a new and useful 10 grate having an inclined section and a dumping section and provides a construction in which the fuel is economically consumed, a more complete combustion is obtained and the efficiency of the boiler thereby greatly increased.

15 It further consists in providing a series of hollow oscillators for the inclined section and through which the draft passes at all times.

It further consists in providing a plurality of blades on the oscillators forming steps for 20 supporting the fuel.

It further consists in regulating the draft in the inclined section whereby the fuel is at the upper portion subjected to a small amount of draft which is increased through- 25 out the extent of the inclined section.

It further consists in providing the dumping section with crushing agitators or choppers, one row of which is adapted to be actuated to support the fuel upon the inclined 30 section during the act of crushing or dumping.

Figure 1 represents a vertical longitudinal section of a grate embodying our invention. Fig. 2 represents a perspective view of one of 35 the oscillators in detached position showing a series of small openings therein. Fig. 3 represents a sectional view of said oscillator. Fig. 4 represents a sectional view of an oscillator with air passages formed by blades. Fig. 5 represents a plan view thereof. Fig. 40 6 represents a side elevation of an oscillator showing the extensions from the sides thereof. Fig. 7 represents a plan view thereof. Fig. 8 is a side elevation of an oscillator and 45 part of its operating means. Fig. 9 is an end elevation with a portion broken away showing two oscillators and a part of their operating means. Fig. 10 represents a sectional view of a portion of the inclined section as 50 shown in Fig. 1 on an enlarged scale with the oscillators in a different position. Fig. 11 represents a side elevation of a dumping section showing the crushing agitators situated in opposite positions ready to crush and 55 dump. Fig. 12 represents a vertical trans-

verse sectional view of one of the crushing agitators of the dump section. Fig. 13 represents a perspective view of one of the oscillators in detached position. Fig. 14 represents a sectional view of a portion of the inclined section showing the oscillators in a different position from that shown in Figs. 1 and 10. Fig. 15 is a bottom perspective view of one of the oscillators on an enlarged scale.

60 Similar numerals of reference indicate corresponding parts in the figures.

Referring to the drawings: We have found in practice that in the class of grates for steam boilers which comprises an inclined and dumping section and to which the fuel is mechanically fed by means of a feeding apparatus suitably located that it is necessary to provide some means whereby the fuel is supplied with the proper amount of draft 70 and further that when the fuel is fed down from the incline upon the dump section, the fuel will not escape from the inclined section and it is further necessary to provide some means when the dumping or crushing action 75 is taking place, to hold the fuel upon the inclined section.

Our invention is designed to accomplish these results and in the drawings we have shown a construction which we have found 80 in practice operates successfully but it will be evident that changes may be made in the construction, the arrangement of the parts may be varied and other instrumentalities may be employed which will come within the 85 scope of our invention and we do not, therefore, desire to be limited in every instance to the exact form herein shown and described, but desire to make such changes as may be necessary.

90 1 designates a grate for steam boilers formed with an inclined section 2 and a dumping section 3.

4 designates the frame for supporting the parts to which are connected the side bars 5 100 which are situated at an incline and form a bearing or support for the inclined section 2.

6 designates rocking bars which are suitably journaled or supported in the sides 5 and which are preferably formed angular. 105 Mounted upon the said rocking bars 6 are the oscillators or agitators which form the fuel bearing surface of the inclined section of the grate and which are formed hollow, in order to provide for the draft, as will be hereinafter 110

described. We preferably desire to employ different forms of oscillators on the incline, one form being shown in Fig. 2 in which 7 designates the bearing face of the oscillator having the depending sides or wings 8, said bearing surface 7, projecting beyond each side of the wings 8, forming the extensions 9. Through said extensions and said bearing face are a plurality of small or minute openings 10 for the passage of air.

11 designates openings in the side wings 8 which are adapted to receive rocking bars 6 and in the drawings the said openings are shown as angular for this purpose. Between 15 said side wings 8 is situated a strengthener 12, which is preferably formed cylindrical, in order to permit the air to circulate freely between it and the bearing face 7 to prevent burning out of the other parts of the 20 oscillator.

13 designates lips or lugs which project rearwardly from the side wings 8 while the front or toe portion of the oscillator is provided with the wall 14 which is adapted to 25 rest upon the lips or lugs 13 on the next oscillator in front thereof as will be clearly seen in Fig. 1. It will be noted that the opening 11 is located near the heel of the oscillator so that the fulcrum is at this point 30 and thus the oscillators will be divided into long and short axes 15 and 16, respectively, as best seen in Fig. 4.

We have shown in Fig. 10 the first row of oscillators similar to that shown in Fig. 2 35 that is, with the small openings, but it will be evident that if desired, we may form other rows with this form of oscillator if desired. The other oscillators in the inclined section 2 as shown in Fig. 1 are formed in a manner 40 shown in Fig. 13 in which 17 designates the side walls or wings of the oscillators between which are blades 18 the upper surfaces of which form steps or supports upon which the fuel will rest, while between the blades, are 45 the passages which permit a free circulation of the air in order to provide a proper draft for the fuel it being noted that the front edge 19 of the blades is inclined to correspond to the inclination of the side walls 17 so that when 50 the oscillators are in their normal position at rest, a straight line is provided from the upper to the lower portion of the said inclined section.

20 designates wings or extensions projecting from each of the side walls or wings 17 which, with those of the next succeeding oscillators, form passages for the air so that there is practically no dead line in the grate and burning out of the oscillators is reduced 60 to a minimum.

It will be noted more particularly from Fig. 1 that the two uppermost lines of the oscillators, formed in conformity with the construction seen in Fig. 13, are made with the 65 blades more closely approaching each other

than in the lowermost series of oscillators. By this means the passages for the air in these upper arms are more restricted, thus making a smaller draft at this point than as the lowermost portion of the inclined section 70 is reached. By this provision it will be understood that the draft is increased from the upper portion to the lower but this arrangement may be varied depending upon the requirements and conditions. One or more of 75 each set of the oscillators is provided with a depending arm 21 which are pivotally connected with a bar 22, which latter in turn is connected with a link 23 which is pivotally connected with a rod 24 leading to a suitable 80 point beyond the furnace for operating the said bar 22 in order to rock the rocking bars 6 and thus actuate the oscillators, it being understood that when the rod 24 is pulled in the proper direction that the bars 6 are rotated in order to lift the toe end of the oscillators, the extreme throw thereof being shown in Fig. 10, attention being called to the fact that as the oscillators are rotated the heel or rear end thereof will be located 90 back of the toe portion or front end 14 of the next higher oscillator so that the fuel, which would be likely to fall from the upper to the lower oscillator, cannot pass through the space 25 formed between the oscillators 95 whereby it will be understood that the coal and fuel will be preserved and directed downwardly to the dumping section, notwithstanding the continued movement of the oscillator. Attention is also directed to 100 the fact that by reason of the inclination at which the oscillators are held the blades 18 are normally situated substantially horizontal, forming the steps or supports upon which the fuel rests so that the same cannot escape 105 through the air openings between the blades and yet a free and constant circulation of air is provided, forming a draft for the fuel at all times and no matter in what position the oscillators are situated.

As is shown in Fig. 14, the oscillators may not be actuated beyond the point where the front or toe portion 14 will pass above the plane of the bearing surface of the oscillators in front thereof, which thus removes any 115 possibility of escape of the fuel, as the fuel is fed down from the inclined section, to pass upon the dumping section 3 of the furnace. The section 3 can be formed of any number 120 of rows of crushing agitators but in the drawings we have shown as two, 26 and 27, mounted upon the cross-rods 28 which latter are suitably supported in the frame of the grate. Said crushing agitators are made of suitable form with the elongated ends 29 and 30 which extend toward each other and which have the side wings 31 and 32 connected at their lower portion by a hub 33 having an angular opening to accommodate the cross-rods 28, it being noted that the sides 125 130

31 and 32 are provided with the open spaces 34 and are divided by a central longitudinal rib 35 which forms the slots 36 in the upper face, all of the openings and slots being provided for the full passage of air to provide a draft, while it will be noted that the upper face of the crushing agitators are preferably curved and are formed with the series of teeth 37 projecting from the sides at the upper portion. The crushing agitators are so arranged upon the rocking bars 28 that when the latter are operated the crushing agitators are rocked in an opposite direction in the arc of a circle so that the free ends are projected upwardly into the bed of the fuel to dislodge the clinkers and break up the fuel and at the same time form a space or opening between the crushing agitators for the passage of the ash, dirt, etc. to the ash receptacle. For the operation of this, the crushing agitator 26 is provided with two depending arms 38 and 39 to the former of which is connected the rod 40 which extends to a suitable point outside of the grate for actuating the same, while connected with the arm 39 is a link 41 the opposite end of which is suitably connected with a lug or projection 42 upon one of the crushing agitators 27 so that it will be seen that when the rod 40 is properly actuated the crushing agitators are rocked into the position seen in Fig. 11 as above described, attention being also called to the fact that by reason of the position which the crushing agitator 26 assumes, that the extending end 29 will be situated at an angle with respect to the plane of the fuel bearing surface of the oscillators of the inclined sections, thus serving to support and hold the fuel upon said inclined sections. From the above it will be seen that the fuel receives a small amount of draft at the upper portion thus providing for a slow combustion at this point while the fuel passes downwardly upon the inclined section the draft is increased a suitable amount, in order to provide for an increase of combustion and for forming a complete combustion, whereby the fuel is economically burned and the efficiency of the boiler is increased. Attention is also directed to the fact that while the blades 18 form steps for holding and retaining the fuel that at the same time, owing to the angle at which the oscillators are held and the location of the same, when at rest, that a perfectly even surface from the top to the bottom is presented which facilitates the downward movement of the fuel as will be evident.

By the arrangement of the air passages in the oscillators, which are located in the inclined section, the currents of air are delivered in an angular direction to the burning fuel in line with the draft which materially assists the same and promotes combustion while there are no angles for the air to turn in

its passage to the fuel. In manipulating or stoking the fire on the inclined section the oscillators are tilted into the position seen in Figs. 10 or 14 where the movement will raise the body of the fuel in sections and cause it to break transversely across the entire width of the grate, leaving the fire in stoked condition to admit the air. The actual cleaning of the fire being accomplished in the dump section as above described.

The plate 43 which is located, as shown in Figs. 1 and 10, at the top of the incline adjacent to the fuel induction opening; to take the place of the usual dead plate, is made sloping on the upper surface to facilitate the passage of fuel and is furnished with an open jaw on the under side to engage the angular head piece, 44; which in turn is bolted at each end to the side bars 5. This said plate is made in sections for ready adjustment and removal in case of repairs, and is maintained in position on the head piece; by means of a loose bolt 45 passed vertically through the same and member 44.

If desired, and we find it expedient, we may make the first row of the oscillators without air openings or passages this being shown in Fig. 1, or more than one row may be made without the air passages, it being understood that depending upon conditions we desire to be able to provide a suitable draft in the inclined section starting the same at the upper row if necessary or at a suitable point in the incline as stated.

While we have shown in Fig. 1, the oscillators 7^x without the openings and the next row of oscillators being made in conformity with the construction shown in Fig. 13, we may if desired, make the row of oscillators next to the row of oscillators 7^x with the small openings 10 as shown in the construction in Fig. 2 or any other arrangement of oscillators may be employed, the arrangement of the oscillators in the incline being arranged according to requirements.

Having thus described our invention, what we claim as new and desire to secure by Letters Patent, is:

1. In a mechanical stoker, a series of hollow oscillators arranged to form an inclined grate and with their upper faces forming a continuous straight inclined surface and having air passages through the fuel-bearing surfaces thereof inclined to said straight surface, means for raising the lower ends of said oscillators, and means for suddenly stopping the downward movement of said lower ends.

2. In a mechanical stoker, a series of hollow oscillators, each oscillator provided with spaced fuel-supporting blades forming air passages between the blades, said oscillators disposed to form with their upper faces a continuous straight inclined fuel-supporting surface, means for raising the lower ends of

said oscillators and permitting them to fall, and means for suddenly stopping the downward movement of said lower ends.

3. In a mechanical stoker, a series of hollow oscillators arranged to form an inclined grate and with their upper faces forming a continuous straight inclined surface and having air passages through the fuel-bearing surfaces thereof inclined to said straight surface, means for raising the lower ends of said oscillators, means for suddenly stopping the downward movement of said lower ends, and a dumping section formed of crushing agitators upon which the fuel is fed from 10 said oscillators.

4. In a mechanical stoker, a series of hollow oscillators, each oscillator provided with spaced fuel-supporting blades forming air passages between the blades, said oscillators disposed to form with their upper faces a continuous straight inclined fuel-supporting surface, means for raising the lower ends of said oscillators and permitting them to fall, means for suddenly stopping 20 the downward movement of said lower ends, and a dumping section formed of crushing agitators upon which the fuel is fed from 25 said oscillators.

5. In a mechanical stoker, a series of hollow oscillators arranged to form an inclined grate and with their upper faces forming a continuous straight inclined surface and having air passages through the fuel-bearing surfaces thereof inclined to said straight 30 surface, means for raising the lower ends of said oscillators, and means for suddenly stopping the downward movement of said lower ends, said passages being graded from the upper to the lower end of the inclined grate.

40 6. In a mechanical stoker, a series of hollow oscillators, each oscillator provided with spaced fuel-supporting blades forming air passages between the blades, said oscillators disposed to form with their upper faces a continuous straight inclined fuel-supporting surface, means for raising the lower ends of said oscillators and permitting them to fall, and means for suddenly stopping 45 the downward movement of said lower ends, said passages being graded from the upper to the lower end of the inclined grate.

7. In a device of the character described, a hollow oscillator having its fulcrum adjacent one end, side walls having continuous 50 upper edges and blades extending between said side walls and forming an acute angle with the upper edges thereof, and a lug projecting rearwardly from a point adjacent its fulcrum to support the toe portion of an adjacent oscillator.

8. In a device of the character described, a hollow oscillator having sides provided with continuous upper edges, a fulcrum adjacent one end of said oscillator, a depending 60 front wall and lugs extending rearwardly

from the sides to support the toe portion of an adjacent oscillator.

9. In a device of the character described, an inclined grate formed of a series of oscillators arranged with their upper faces forming a continuous straight inclined surface and provided on the fuel bearing surface with air passages of different capacities to deliver in an angular direction with relation to the upper face of the grate, large and small 70 quantities of air at various points to the body of the fuel, means for raising the lower ends of said oscillators and means for suddenly stopping the downward movement of said lower ends.

10. In a device of the character described, an inclined grate formed of hollow oscillators arranged with their upper faces forming a continuous straight inclined surface and spaced blades thereon forming intervening 80 air passages adapted to deliver air in an angular direction to the upper face of the grate, means for raising the lower ends of said oscillators and means for suddenly stopping the downward movement of said lower ends.

11. In a device of the character described, an inclined grate formed of a series of oscillators, arranged with their upper faces forming a continuous straight inclined surface and provided on the fuel bearing surface with a 90 plurality of minute air orifices extending in an angular direction with relation to the face of the grate to deliver streams of air to the fuel, means for raising the lower ends of said oscillators and means for suddenly stopping the downward movement of said lower ends.

12. In a device of the character described, an inclined grate formed of a series of hollow oscillators arranged with their upper faces forming a continuous straight inclined surface and having air spaces to deliver the air in an angular direction with relation to the face of the grate said oscillator being mounted to one side of the center to swing upwardly to dislodge the fuel and allow the latter to pass downwardly, means for raising the lower ends of said oscillators and means for suddenly stopping the downward movement of said lower ends.

13. In a device of the character described, a grate having an inclined section and a dumping section, disposed adjacent the lower end of the inclined section and comprising connected crushing agitators suitably mounted to rotate in opposite directions with their 115 opposed faces adapted to be turned into a substantially vertical position one of which is adapted to support the fuel on the inclined section while cleaning and adapted to break up, crush and discharge the clinkers into the 120 fire pot.

14. In a device of the character described, an inclined grate, a dumping section formed of a series of connected crushing agitators 130 having elongated approaching ends adapted

to be swung upwardly into substantially vertical position to form a gap therebetween to crush and remove the clinkers or other refuse from the fire, said dumping section being arranged adjacent the lower end of the inclined grate.

15. In a grate, an oscillator consisting of depending side wings, spaced from each other, exterior and interior spaced inclined 10 blades between said side wings, providing air passages between the blades and forming the fuel bearing surface and inclined to the upper edges of the sides, said oscillator having transverse angular openings through said 15 side wings, located near one end or heel thereof, and a cylindrical projection between the aforesaid side wings.

16. In a grate, a rocking bar, an oscillator mounted upon said rocking bar and consisting 20 of depending side wings, exterior and interior spaced inclined blades, the latter being between said side wings, there being air passages between said blades said oscillator having a transverse angular opening disposed 25 eccentrically with relation to the length of said oscillator, a cylindrical projection surrounding said opening, and a depending arm adapted for connection with the next succeeding chopper.

30 17. In a grate, a rocking bar, an oscillating chopper mounted upon said rocking bar and consisting of depending side wings, exterior and interior spaced inclined blades, the latter being between said side wings and forming 35 air passages between the blades, said oscillating chopper having a transverse angular opening disposed eccentric with relation to the length of said chopper, a cylindrical projection surrounding said opening, and a depending arm bifurcated at the lower extremity, intermediate pivot center and tie bar 40 adapted to receive and communicate motion to other choppers.

18. In a grate, an oscillator, consisting of 45 side and front walls, and a plurality of fuel supporting blades connecting said side walls, the forward edges of said blades arranged at an acute angle to the upper edges of said side walls, said side walls being provided near 50 their rear ends and below said blades with openings for an agitator bar.

19. In a grate, an oscillator, consisting of 55 side and front walls, and a plurality of fuel supporting blades connecting said side walls, the forward edges of said blades arranged at an acute angle to the upper edges of said side walls, said oscillator having rearwardly extending supporting lugs adapted to support the toe portion of an adjacent oscillator.

60 20. In a grate, an oscillator, consisting of side and front walls, a plurality of fuel supporting blades connecting said side walls, the forward edges of said blades arranged at an acute angle to the upper edges of said side 65 walls, the front wall constituting a toe por-

tion adapted to rest on a portion of the next adjacent oscillator.

21. In a grate, an oscillator, consisting of side and front walls, and a plurality of fuel supporting blades connecting said side walls, 70 the forward edges of said blades arranged at an acute angle to the upper edges of said side walls, said oscillator having rearwardly extending supporting lugs and the front wall constituting a toe portion adapted to rest on 75 the supporting lugs of the next adjacent oscillator.

22. In an inclined grate, the combination of a plurality of oscillators disposed end to end and having their axes arranged transversely of the grate, the center of gravity of said oscillators being on the lower or discharge side of their axes, means for raising the lower sides of said oscillators and permitting them to fall, and means for suddenly 80 stopping the downward movement of said lower sides when the oscillators are in a position to form a substantially straight inclined fuel-bearing surface, whereby the fuel is agitated and fed from the upper to the lower 85 side of the grate.

23. The combination with an inclined grate consisting of a row of oscillators having substantially horizontal openings therethrough terminating at the upper surface, 95 said oscillators being successively disposed end to end and lying normally in substantially the same plane of means for actuating said oscillators, said means being constructed to allow the lower ends of the oscillators to 100 return to normal position by gravity.

24. The combination with an inclined grate consisting of a row of hollow oscillators having substantially horizontal openings therethrough terminating at the upper 105 surfaces, said oscillators being successively disposed end to end and lying normally in substantially the same plane, of means for actuating said oscillators, said means being constructed to allow the lower ends of the 110 oscillators to return to normal position by gravity.

25. The combination with an inclined grate consisting of a row of oscillators having approximately horizontal perforations and 115 arranged end to end and each provided also with a cutting toe at its free lower end, in combination with means for actuating the oscillators and arranged to lift the oscillators at their lower ends and to allow them to return to normal position by gravity.

26. The combination with an inclined grate consisting of a row of oscillators having suitable air openings therein and arranged end to end, each oscillator being provided 125 with a cutting toe at its free lower end, and with a stop for an adjacent oscillator on its heel portion.

27. The combination of a series of oscillators normally lying end to end in an in- 130

clined plane, of means for actuating said oscillators to agitate the fuel, the oscillators being so mounted as to cause the toe of one to overlap the heel of another when the toes of the oscillators are raised, thereby preventing fuel from passing down between the same.

28. The combination of an inclined grate, connected crushing agitators mounted at the front of the same and means for separating

said agitators by an upward movement thereof, said means being adapted to set one agitator across the path of the fuel to hold it on the grate.
